(57) **CLAIM**

The ornamental design for a brush handle, as shown and described.

DESCRIPTION

FIG. 1 is a top side perspective view of the brush handle of the present invention;

FIG. 2 is a side elevation view of the brush handle illustrated in FIG. 1;

FIG. 3 is a top plan view of the brush handle illustrated in FIG. 1;

FIG. 4 is a bottom plan view of the brush handle illustrated in FIG. 1; and,

FIG. 5 is a reduced side elevation view of the brush handle design of the present invention in combination with a toothbrush.

The broken line structure shown in FIG. 5 is for illustrative purposes only and forms no part of the claimed design.
